UNITED STATES PATENT OFFICE.

CHARLES L. MCCUEN, OF DETROIT, MICHIGAN, ASSIGNOR TO ISKO, INCORPORATED, OF DETROIT, MICHIGAN, A CORPORATION OF MICHIGAN.

DESIGN FOR A FLY-WHEEL OR SIMILAR DEVICE.

51,236.

Specification for Design.

Patented Sept. 4, 1917.

Application filed July 9, 1917. Serial No. 179,562. Term of patent 7 years.

To all whom it may concern:

Be it known that I, CHARLES L. MCCUEN, a citizen of the United States, residing at Detroit, in the county of Wayne and State of Michigan, have invented a new, original, and ornamental Design for a Fly-Wheel or Similar Device, of which the following is a specification, reference being had to the accompanying drawing, forming a part thereof.

The figure is a side elevation of a fly-wheel or similar device, embodying my design.

I claim:

The ornamental design for a fly-wheel or similar device as shown.

CHARLES L. MCCUEN.
